UNITED STATES PATENT OFFICE.

FREDERIC A. PARKHURST, OF CLEVELAND, OHIO, ASSIGNOR TO THE ALUMINUM CASTINGS COMPANY, OF CLEVELAND, OHIO, A CORPORATION OF OHIO.

COMPOSITE PISTON FOR INTERNAL-COMBUSTION MOTORS.

1,329,823.

Specification of Letters Patent.

Patented Feb. 3, 1920.

Application filed July 24, 1916, Serial No. 110,845. Renewed October 24, 1918. Serial No. 259,596.

To all whom it may concern:

Be it known that I, FREDERIC A. PARKHURST, a citizen of the United States, residing at Cleveland, in the county of Cuyahoga and State of Ohio, have invented certain new and useful Improvements in and Relating to Composite Pistons for Internal-Combustion Motors, of which the following is a specification.

- 10 This invention relates to pistons for use particularly in internal combustion motors. One of the objects of my invention is to produce a simple, light, durable and efficient skirted, composite piston peculiarly adapted 15 to meet the conditions which exist within an internal combustion motor cylinder, including the stresses and strains imposed upon the piston, principally during the explosion stroke and by the high heat generated at 20 this time, which heat must be efficiently and economically (a) utilized in the translation of heat into mechanical energy and (b) that not translated into mechanical energy properly dissipated.

- 25 A further object of my invention is the production of a light weight piston adapted to overcome in a large measure the difficulties known as piston slap and oil pumping.

My present invention comprises improvements on the invention of Joseph H. Bamberg disclosed in his Letters Patent of the United States No. 1,296,589. It contemplates providing a relatively light, durable composite piston, utilizing the principal advantages characteristics of the piston invented by Mr. Bamberg and employing a guiding section of material of greater resistivity to wear than the metallic alloys of aluminum now commercially used in piston construction, some of which are referred to in Mr. Bamberg's said patent.

Purely for the purposes of disclosure herein I have selected to illustrate and describe one construction of internal combustion motor, skirted piston and a modification thereof embodying my improvements.

In the drawings, Figure 1 is a side elevation of a piston embodying my improvements.

- 50 Fig. 2 is a section on the line 2—2, Fig. 1. Fig. 3 is a section on the line 3—3, Fig. 2. Fig. 4 is a bottom plan view.

- Fig. 5 is a section and Fig. 6 a bottom plan view of a modified construction of composite piston embodying my invention.

1 is the skirt, body or guide section of the piston, which may be made preferably of sheet metal or any material suitable to resist wear in operation within an internal combustion motor cylinder, such for example as a section of drawn steel tubing or steel stamping. This guide section 1 is formed with aligned diametrically opposed apertures 1^a, 1^b, which preferably are concentric with the axis of the wrist pin bosses, 60 later to be described, to permit the insertion and withdrawal of the wrist pin, as desired, in the well known manner. At its lower end the metal of the section is bent inwardly and back upon itself, as indicated 65 at 1^c, and formed with an annular inner cylindrical section 1^d of reduced diameter. In order to lighten as much as possible the sheet metal part of the piston, apertures 1^e may be formed through the inwardly turned 70 wall 1^c.

3 indicates a combined piston head and connecting piece having an end wall 3' and downwardly extending side walls 3^a. The periphery of the side walls adjacent the end 80 wall 3' may be suitably recessed as indicated at 3^d to receive piston rings of any well known construction and therebelow may carry diametrically opposed, inwardly extending, annular wrist pin bosses 3^e.

The section 3^e at the lower end of this combined head and connector may be secured to the lower end of the skirt 1 in any suitable manner. In Figs. 2, 3 and 4 I have shown this connection to be effected by internally screw-threading the section 3^e and externally screw-threading the outer surface of portion 1^d of the sheet metal section of the piston. When this connection is made, if desired the wall 3^e may be heated so as to 95 expand it considerably and the screw threaded portions of the parts 1 and 3 may be screwed together while the part 3^e is thus heated so as to obtain a shrink fit on this threaded connection.

The part 3 may be made of any desired material having a relatively low specific gravity and may be formed in any suitable manner. I prefer to make it of an aluminum alloy cast in a permanent mold and 105 suitably poured and chilled so that its structure will be relatively fine-grained and non-porous and the eutectic will substantially surround the excess substance in the structure. For example, this combined head and 110

connector 3 may be made in accordance with the invention of Joseph Bamberg as set forth and described in his said Letters Patent of the United States No. 1,296,589.

5 Where so constructed suitable strengthening webs or ribs 3^g may be provided at the head end of the piston, in the now well known manner.

In Fig. 5 I have illustrated another way 10 of connecting the lower end of the element 3 to the inner portion at the lower end of the element 1. In this embodiment of my invention the upper end of the inwardly and upwardly turned portion 1^e of the skirt is 15 internally screw-threaded, as indicated at 1^h, and the section 3^f at the lower end of the combined head and connector 3 is correspondingly externally screw-threaded. When this connection is made, if desired, the screw- 20 threaded section 1^h of the skirt may be heated so as to expand it considerably, and the screw-threaded portion of the parts 1 and 3 then may be screwed together while the portion 1^h of the guide section is thus heated so 25 as to obtain a shrink fit on this threaded connection.

Should it be deemed advisable to lock the section 3^f to the adjacent inner annular portion of the skirt 1, this may be accomplished 30 after the parts are screwed together by slight distortion or mutilation of one or more of the screw threads, in any well known manner, not shown.

A plurality of holes 3^x are provided 35 through the sheet metal section, preferably where the metal is bent back upon itself to form the lower end of the piston. These holes or ducts provide oil escapes or drain passages for lubricant or oil which may collect 40 between the skirt 1 and the lower end of the combined piston head and connecting element 3.

It will be understood that the sleeve or skirt 1 may be constructed so as snugly to 45 fit the inner wall of the motor cylinder, which is commonly made of iron or steel, whereas the portion of the head 3 above it may be given a considerable amount of clearance between its outer periphery and the 50 inner wall of the cylinder to allow for all necessary expansion of the head due to the high temperatures to which it is subjected. The heat absorbed by the head is transferred 55 downwardly by the side walls 3^a to the lower end of the skirt 1, and much of it is dissipated by radiation, so that the skirt is kept 60 relatively cool and may be readily lubricated to provide and maintain the proper working relationship between it and the inner wall of 65 the motor cylinder with which it co-acts. The fit between the skirt and the inner wall of the cylinder, as before indicated, may be a snug sliding fit, and preferably the area of the skirt which co-acts with the inner wall 70 of the motor cylinder is such as to insure

against slapping or rapping of the piston against the inner wall of the cylinder. In fact, objectionable so-called piston slap, incident to the operation of numerous types of pistons for use in internal combustion 75 motors, substantially is eliminated by the use of a piston constructed in accordance with my invention as shown in the drawings. Furthermore, a piston embodying my improvements herein described practically 80 eliminates so-called "oil pumping" or transfer of an undue amount of oil or lubricant from the crank case to the upper end of the piston, resulting in undesirable smoking and undue and troublesome carbonization, among 85 other things.

Due to the fact that the sleeve or skirt is maintained relatively cool under all normal working conditions, the possibilities of scoring of the inner walls of the cylinder are 85 practically eliminated.

The upper end of the skirt 1 is separated 90 from the head 3 by an air gap. In the drawings, purely for the purpose of illustration, this air gap is shown relatively wide. The presence of this air gap or air space between the upper edge of the skirt or body section 1 and the adjacent edge of the piston head, insures that the heat absorbed by the piston head principally will be transmitted 95 inwardly and downwardly so that such portions of it as does reach the skirt or body by conduction will do so at the lower end of the skirt and will not be sufficient in amount to cause the necessary expansion of the skirt to 100 effect binding between the skirt and inner wall of the cylinder or scoring. While this air gap, as above stated, has been shown relatively wide for the purpose of illustration, it will be understood that my invention contemplates any sort of a separated relationship between the upper end of the skirt and the adjacent head 3 because of which heat will not be transmitted efficiently or readily from said head to the skirt. It will be 110 understood that this relationship might be that even of a poor mechanical fit or joint which would be a poor conductor of heat as compared with the metal of the side walls 3^a, so that such heat as did pass from the 115 head to the guide section 1 would do so principally by way of the side walls 3^a, rather than from the head to the upper end of the skirt 1.

It will be understood that by making the 120 skirt or guide part of my piston of iron or steel I not only secure good wearing qualities but also a coefficient of thermal expansion much smaller than those of the light weight alloys such as aluminum alloys. 125 Both this low coefficient of expansion and the low working temperature of the piston skirt favor the close working fit of the skirt in the engine cylinder and, at the same time, full advantage is taken of the light weight 130

material of the head and connecting part to reduce the weight of the piston.

By making the head and connecting part of the piston of light weight metal such as aluminum alloy and by forming the skirt of relatively thin steel tubing, the weight of my improved composite piston is made comparable with that of pistons made entirely of aluminum alloys. This light weight is, of course, of material advantage in reducing the weight of the reciprocating parts of the engine, and pistons of my improved construction will be found to operate comparatively noiselessly, smoothly and efficiently.

Certain features of the subject-matter herein disclosed but not claimed, are claimed in my co-pending application Serial No. 110,844, filed July 24, 1916.

To those skilled in the art, many modifications of and widely differing embodiments and applications of my invention will suggest themselves, without departing from the spirit and scope thereof. My disclosures and the descriptions herein are purely illustrative and are not intended to be in any sense limiting.

What I claim is:

1. A composite piston for an internal combustion motor comprising a head, wrist pin bosses and an extension below said wrist pin bosses cast integrally of a metallic alloy having a relatively low specific gravity in comparison with iron, and a sheet metal guide section having an outer wall adapted to engage the inner wall of a motor cylinder and a section bent inwardly and upwardly from the lower end of said outer wall and secured to said cast extension below said bosses.

2. A composite piston for an internal combustion motor comprising a head, wrist pin bosses and an extension below said wrist pin bosses cast integrally of a metallic alloy having a relatively low specific gravity in comparison with iron, and a sheet metal guide section having an outer wall adapted to engage the inner wall of a motor cylinder and a section bent inwardly and upwardly from the lower end of said outer wall and secured to said extension below said bosses by a shrunk screw threaded connection between the parts.

3. A composite piston for an internal combustion motor comprising a head, wrist pin bosses and an extension below said wrist pin bosses cast integrally of a metallic alloy having a relatively low specific gravity in comparison with iron, and a sheet metal guide section having an outer wall adapted to engage the inner wall of a motor cylinder and a section bent inwardly and upwardly from the lower end of said outer wall and secured to said cast extension below said bosses, the upper edge of the outer wall of said guide section being separated from the adjacent

wall of the head by a relatively small air gap.

4. A composite piston for an internal combustion motor, comprising a sheet metal guide section having an outer wall adapted snugly to fit the inner wall of a motor cylinder, the lower portion of said guide section being turned inwardly and upwardly to form an inner portion of reduced diameter at its upper inner end, and a head, wrist pin bosses and extension below said bosses cast integrally of a metallic alloy having a lower specific gravity than iron, and said extension being secured below said bosses to said upper end of said inner reduced portion of said sheet metal guide section.

5. A composite piston for an internal combustion motor, comprising a sheet metal guide section having an outer wall adapted snugly to fit the inner wall of a motor cylinder, the lower portion of said guide section being turned inwardly and upwardly to form an inner portion of reduced diameter at its upper inner end, and a head, wrist pin bosses and extension below said bosses cast integrally of a metallic alloy having a lower specific gravity than iron, and said extension being secured below said bosses by a screw threaded connection to said upper end of said inner reduced portion of said sheet metal guide section.

6. A composite piston for an internal combustion motor, comprising a sheet metal guide section having an outer wall adapted snugly to fit the inner wall of a motor cylinder, the lower portion of said guide section being turned inwardly and upwardly to form an inner portion of reduced dimensions at its upper inner end, and a head, wrist pin bosses and extension below said bosses cast integrally of a metallic alloy having a lower specific gravity than iron, and said extension being secured below said bosses to said upper inner end of said reduced portion of said sheet metal guide section, the upper edge of the outer wall of said guide section being separated from the adjacent wall of the head by a relatively small air gap.

7. A composite piston for an internal combustion motor, comprising a cylindrical sheet iron guide section having its outer wall adapted snugly to fit the inner wall of a motor cylinder, the lower free end of said guide section being bent and drawn inwardly and upwardly to form an inner reduced portion, and a head, wrist pin bosses and extension below said bosses cast integrally of a metallic alloy having a lower specific gravity than iron, and said extension being secured below said bosses to the adjacent free end of said reduced portion of said sheet metal cylinder.

8. A composite piston for an internal combustion motor, comprising a head, wrist pin bosses and an extension below said wrist pin

- bosses cast integrally of a metallic alloy having a low specific gravity and a high coefficient of expansion in comparison with iron, and a guide section made of wear-resisting metal having a low coefficient of expansion in comparison with the said metallic alloy and formed with an elongated cylindrical wall adapted to slidably engage the inner wall of the motor cylinder, the guide section having its upper end separated from the head part of the piston by an air space and its lower end extended inward and upward and secured to the said extension below the wrist pin bosses.
9. A composite piston for an internal combustion motor, comprising a head, wrist pin bosses and an extension below said wrist pin

bosses cast integrally of a metallic alloy having a low specific gravity and a high coefficient of expansion in comparison with iron, 20 and a guide section made of wear-resisting sheet metal having a low coefficient of expansion in comparison with the said metallic alloy and formed with an elongated cylindrical wall adapted to slidably engage the 25 inner wall of the motor cylinder, the guide section having its upper end separated from the head part of the piston by an air space and its lower end extended inward and upward and secured to the said extension below the wrist pin bosses. 30

In testimony whereof I affix my signature.

FREDERIC A. PARKHURST.
